Inventor:
Henry D. Padget.
By John C. Higdon
Attorney.

UNITED STATES PATENT OFFICE.

HENRY D. PADGET, OF ST. LOUIS, MISSOURI.

BRASS AND PACKING GUARD FOR CAR-AXLE BOXES.

Application filed April 4, 1921. Serial No. 458,451.

To all whom it may concern:

Be it known that I, HENRY D. PADGET, a citizen of the United States, residing at the city of St. Louis, State of Missouri, have invented certain new and useful Improvements in Brass and Packing Guards for Car-Axle Boxes, of which the following is a specification containing a full, clear, and exact description, reference being had to the accompanying drawings, forming a part hereof.

My invention consists in the novel construction and combination of parts herein-after particularly described and distinctly claimed.

The object of my invention is to provide a brass protector and packing-guard, or attachment for car axle-boxes, which shall so preserve the packing-material, and which shall be so economical in the use of oil or other lubricant that it will only be necessary to pack the box once each year, instead of every day or oftener, as is necessary with the axle-box constructions heretofore known to me.

A further object of my invention is to improve upon the device shown and described in my United States Patent No. 1,368,830 dated February 15, 1921.

Heretofore, the axle-boxes have operated most satisfactorily in hot weather, and have been least efficient in cold weather, because the lubricant is kept warm and thin in hot weather, and so reaches the surfaces of the journals and brasses, while in cold weather the lubricant congeals and fails in many instances to prevent the journal from overheating, cutting and breaking; causing wrecks and damage, to say nothing of loss of life and limb.

A further object of my invention is to provide a brass protector and packing guard which shall prevent accidental lateral displacement of the journal and positively lock the packing in the axle-box, and thereby prevent it from being stolen.

Heretofore, car axle-boxes have been robbed by tramps and boys, and the stolen packing has been used to build fires by such persons in cold weather; the packing being cold and gummy crowds its way out of the front of the box and drops upon the ground and is lost; while at other times the packing heaps up against the lid of the box, leaving the journal and brass bare and

devoid of any lubrication, with the inevitable result of a "hot" box and possible accident, because of the Babbitt or other soft metal lining melting from the brass bearing and allowing cutting to take place.

After the journal has been worn or cut, as just described, repacking after cooling, has prevented the cut journal from burning completely off, if discovered in time; but in many instances the "hot" box and cut journal have not been discovered in time to prevent a wreck of the train, killing and maiming passengers; if the train be a passenger-train; or, if the train be a freight train carrying oil tank-cars filled with gasoline or other inflammable material, such cars have been blown up by a hot box, causing loss of life, and destroying millions of dollars worth of property, entailing costly damages.

In the drawings, Fig. 1 is a sectional side-elevation of the main body of a car axle-box, having my invention in place therein.

Fig. 2 is a front-end elevation of the box, as it appears before placing my invention therein.

Fig. 3 is a sectional side-elevation of my invention, detached, the section being taken on line 3-3 of Fig. 5.

Fig. 4 is a view similar to Fig. 3, but modified by the omission of the abutment fingers.

Fig. 5 is a top plan-view of my invention on a smaller scale, detached, and having its inner end slightly tilted upwardly, to the position most convenient for inserting the device in the axle-box, and

Fig. 6 is a detail section of a modified base-member.

The numeral 1 designates the axle-box, having the customary bearing-brass 2 and wedge 3, and carried by the journal 4 of the car-axle 5.

Said brass 2 has the usual lugs 6 on its opposite edges, on which the edges of the said wedge rest.

The base or body of my improved brass-protector and packing-guard consists of a flat plate of metal 7, which is fixed in a horizontal position in the outer end of the box 1, resting upon and pressing down the body of oiled waste or packing 8^a thereat, to hold said packing in place at all times while the car is in service.

Formed in the upper surface of the said body 7 are a series of oil-grooves 8, and formed integral with the ends of said body are opposite vertical end-flanges 9, which are provided with bolt apertures through which are passed the attaching-bolts 10 or other fastening-devices, used in fixing said body inside of the said box 1.

The said bolts or fastening-devices 10 are sufficiently long to be passed through apertures 10^a formed in the vertical side-walls of the axle-box 1, thence through registering apertures in the outer ends of inclined lug-rest supporting-arms 11, and then through registering apertures of the said vertical end-flanges 9 of the said body 1, and the heads of said bolts are rounded and are located upon the exterior of said box, to prevent turning of the bolts from the exterior of the box, the nuts of said bolts being located upon the interior of said box. See Fig. 1. Of course, before the device shown in Fig. 5 is placed in the axle-box 1 the said bolts 10 should be removed, and (after the device has been placed in said box) said bolts should be first passed through the bolt-holes of the box, and thence into and through the registering bolt-holes in the adjacent overlapping end-flanges 9 and supporting-arms 11, as shown in Fig. 1.

Lug-rests 12 having a horizontal supporting-flange 14 and an angular vertical inner wall 15, are formed integral with the inner ends of the said lug-rest supporting-arms 11, for the purpose of supporting, and holding in place, the said brass 2 when the car is jerked and stopped suddenly in switching and coupling operations, and also in derailments.

In some cases, where there is sufficient space in the said box 1 on opposite sides of the journal 4, I form integral with the said body 7, at the ends of the latter, two parallel horizontal fingers 16, which extend into the spaces between the vertical side-walls of the box and the said journal, for about one-half the length of said journal, to thereat bear upon and securely hold down the said packing 8^a.

Said fingers 16 also act as solid abutments, to limit the relative lateral movement of the said journal 4 and the box; said fingers being made of a solid body of hard metal that is practically incompressible.

When a car carrying an axle-box having my invention within it is jerked back and forth violently, in switching and coupling operations, or in derailments, the abutment fingers 16 will effectually hold the journal 4 against accidental lateral displacement, which might otherwise occur, and result in breaking the brass 2 and rendering the same worthless.

Furthermore, the brass 2 and the wedge 3 will be securely held against displacement

in shocks and accidents, by the said lug-rests 12, in the recesses or pockets of which the opposite brass-lugs 6 are located.

Said lug-rests 12 may really be termed lug-brass pockets, as the said brass-lugs are 70 enclosed by the walls of said pockets on all sides except the top and inner side.

In boxes which have insufficient room at the side of the journal for the insertion of said fingers 16, the modified form of my 75 invention shown in Fig. 4 should be used, as that form has the fingers omitted.

In Figs. 5 and 6 I have illustrated a means for lengthening and shortening the said flat body member 7 of my invention, so that the 80 device may be quickly adjusted to fit wide or narrow boxes.

In such a case, the said body 7 is made in two sections which slide upon each other longitudinally, and are fastened together 85 after the width of the box is determined, by tightening a screw or bolt 17, which operates in a longitudinal slot 18 formed in the lower section, in the present instance.

Said oil-grooves 8 in the upper face of the 90 horizontal body member 7, prevent some of the oil from running out of the box through the door-opening thereof, in cases where (as here shown) the top of said body member is about in the same horizontal 95 plane as that of the bottom of said door-opening.

By the use of my invention, the collar, rim, or flange at the outer end of the said 100 journal 4, can be done away with, as entirely unnecessary. The past and present use of said collar, rim, or flange, is principally for the purpose of keeping the brass 2 in its proper place in the box, and therefore, as my invention efficiently performs such service, in the manner previously described, the 105 said outer collar or rim will be unnecessary.

My invention, as above described, firmly holds the brass 2 in its proper position, and permits the use of a rimless or collarless 110 journal, which has long been needed, because the rim or collar at the outer end of the journals heretofore, and now, in use, obstructs the view of the inspector, and is greatly in the way in placing and removing 115 the brass.

By omitting said rim or collar, the inspector will have a free and clear view of the journal, and he can therefore more readily detect and remedy any defect in the journal or brass; and besides, (with no end rim on the journal) the placing and removal of the brass would be greatly facilitated.

The operation of my invention will be readily understood from the above description.

I claim:—

1. An improved journal-brass and packing-guard for car-axle boxes, comprising a flat body-member having at its opposite ends 130

parallel vertical perforated flanges; brass-lug supporting pockets; inwardly extending opposite arms having their outer ends attached to the said perforated flanges of said body-member, and supporting said pockets at their inner ends; and fastenings for securing said perforated flanges in place upon the interior of a car-axle box.

2. The combination with the elements mentioned in the above claim 1, of parallel horizontal solid abutments the outer ends of which are secured to the said flat body-member, and the said abutments extending inwardly in a horizontal position into the spaces at opposite sides of the journal, and adapted to hold the latter and the vertical side walls of the box in relatively operative positions during shocks and derailments,

and also to rest upon and press down the packing that is in said box, and prevent its surreptitious removal. 20

3. The combination with the elements mentioned in the above claim 1, of said flat body-member constructed in two slidble sections, so that said member may be lengthened or shortened to fit in boxes of different widths; and means for fastening said sections in position after they have been adjusted to the desired length. 25

In testimony whereof, I have signed my name to this specification in presence of two subscribing witnesses.

HENRY D. PADGET.
